Patented Dec. 18, 1962

194,250

SUBMERSIBLE SUMP PUMP

Kenneth R. Lung, % The Tait Manufacturing Company,
500 Webster St., Dayton, Ohio

Filed May 31, 1961, Ser. No. 65,406

Term of patent 14 years

(Cl. D65—1)

FIG-2

FIG. 1 is a perspective view of a submersible sump pump embodying my new design; and

FIG. 2 is a top plan view thereof.

The side opposite that shown in FIG. 1 is substantially the same as that shown.

I claim:

The ornamental design for a submersible sump pump, as shown and described.
